(57) **CLAIM**

The ornamental design for a carrier apparatus for pneumatic tube delivery system, as shown and described.

DESCRIPTION

FIG. 1 is a frontal perspective view of a carrier apparatus for pneumatic tube delivery system illustratively incorporating our present design;

FIG. 2 is a top elevational view thereof;

FIG. 3 is a front elevational view thereof;

FIG. 4 is a right side elevational view thereof, an opposing left side elevational view being a mirror reflection of such right side elevational view;

FIG. 5 is a rear perspective view of the carrier apparatus for pneumatic tube delivery system shown in FIG. 1;

FIG. 6 is a rear perspective view thereof in a vertical orientation, as viewed from a first viewing angle; and,

FIG. 7 is another rear perspective view thereof in a vertical orientation, as viewed from a second viewing angle.

The broken lines in FIGS. 1 and 4 are directed to environment and are for illustrative purposes only; the broken lines form no part of the claimed design.

1 Claim, 6 Drawing Sheets
